ARC EXTINGUISHING ATTACHMENT FOR
AIR-BREAK SWITCHES

Tomlinson F. Johnson, Atlanta, Ga.

Application March 23, 1950, Serial No. 151,388

6 Claims. (Cl. 200—146)

1

This invention relates to high tension switches or circuit interrupters having provision for extinguishing the arc under heavy loads when the switches are operated to isolate portions of a line. Among other objects, the invention aims to provide a simplified and effective arc extinguishing or interrupter attachment for use on group operated air-break switches, whereby the switches may be employed for disconnecting or isolating sections of heavy voltage lines operating under full loads.

Another aim of the invention is to provide a simplified and effective arc extinguisher or interrupter device, adapted to be applied to ordinary air-break switches having vertically tiltable or swinging blades and equipped with arcing horns.

Other aims and advantages of the invention will appear in the specification when considered in connection with the accompanying drawings, wherein:

Fig. 1 is a side elevation of a single switch having the preferred form of attachment applied thereto;

Fig. 2 is a fragmentary view, similar to Fig. 1, showing the switch in its partially opened position;

Fig. 3 is a fragmentary top plan view of the arc extinguishing attachment shown in Fig. 1;

Fig. 4 is a fragmentary vertical sectional view of the attachment;

Fig. 5 is a sectional view taken on the line 5—5 of Fig. 4; and

Fig. 6 is a sectional view taken on the line 6—6 of Fig. 4.

Group operated air-break switches of the type disclosed are employed for disconnecting and isolating sections of high voltage transmission lines. Unless they are provided with special load breaking attachments, such switches cannot be operated under full load conditions. They can break only limited transformer charging currents and will be severely damaged, due to arcing, under full loads. It is, therefore, a principal object of the present invention to provide a simplified and very effective arc extinguishing attachment for high tension, air-break switches, which will enable them to be operated under load conditions without damage to the switch contacts.

Referring more particularly to the drawings, Fig. 1 shows an ordinary air-break switch of the tilting insulator or vertical swinging blade type to which the preferred form of the attachment is applied. It will be understood, however, that the attachment is applicable to other types of air-

2

break switches, wherein the blades are mounted to swing in vertical planes.

In the illustrated example, a single switch is shown as being mounted on a channel or base member 10 carrying a fixed insulator 11 and stationary contact having the usual switch jaws 12 and a tiltable insulator 13 carries a pivotally mounted blade 14 adapted to be swung vertically into and out of contact with the jaws 12. The line or conductor 15 is pivotally connected to the bracket of the swinging blade and the blade bracket carries a pair of parallel, resilient arcing horns 16 made of heavy wire, such as silicon bronze.

15 The stationary contact is of the usual type and includes a bracket 17 having a base plate 18 to which the conductor 19 is connected. In accordance with this invention, a supporting bracket plate 20 is secured to the base plate 18 and has upstanding ears 21 for carrying the arcing attachment. A horizontal shelf member 22 has a vertical arm 23 secured to the upstanding ears 21 by a pair of bolts 24. This shelf also has an integral upstanding ear 25 to which an inverted, U-shaped arc horn 26 is connected by a clamping plate 27 and bolts 28. The movable arcing horns 16 are adapted to straddle the stationary arcing horns in the usual manner.

20 The outer end portion of the shelf is provided with a trough-shaped supporting member 29 having an upstanding flange 30 at its front end sides, so that water will drain out of it and cannot accumulate and freeze in it. An upstanding arcing conductor rod 31 is screw threaded into a vertical opening in the trough-shaped member. An interrupter tube 32, preferably made of hard, fibrous insulating material, is supported for sliding movement on the arcing conductor rod 31 by means of a hub-shaped guide member 33, made of aluminum or other light weight material. It loosely engages the lower end of the rod and has a cylindrical flange 34 connected to the lower end of the tube by means of a pair of diametrically opposite arms 35, the arrangement being such that the hub member does not close the lower end of the tube and rests on the bottom of the trough-shaped member 29. An aluminum cylinder or skirt 36 surrounds the guide member 33 and extends to a point near the bottom of the trough 29 to direct the gas into the trough. The cylindrical sleeve and flange 34 of the hub-shaped guide member are shown as being connected to the lower end of the tube by screws 37. The upper end of the tube is shown as having a removable bronze plug member 38 inserted therein with

a pair of radial lugs 39 engaging radial notches in the end of the tube. It is held in place by a cap 40 telescoped over and secured to the upper end of the tube by screws 41. The cap is shown as having a plurality of cam shaped ribs 42 adapted to guide the wires of the arcing horns 16 downwardly over the cap to engage their lower edges 43, so that, when the switch is opened, the horns will lift the tube. The lower portions of the cam shaped ribs are shown as being rounded at 44 to act as guiding cams, so that the wires of the horn 16 will spread apart and be disengaged from the cap in case the tube is stuck on the arcing rod 31 during its lifting movement. A short conductor rod 45 is shown as being threaded through an upstanding boss 46 on the cap member 39 and through the upper end portion of the plug 38 so that its lower end contacts the upper end of the arcing rod 31. It is held in its adjusted position by a jamb nut 47 and extends only a short distance above the upper end of the cap. This rod also serves as a guide for the movable arcing horns 16 when the switch is being closed.

As will be seen in Fig. 1, the lower ends or shoulders of the cap member 39 are above the level of the upper end of the stationary U-shaped horn 26, so that the movable arcing horns 16 will engage the bottom of the cap during the opening movement of the switch blade to re-establish the circuit through the interrupter and lift the tube as the blade swings open. As soon as the tube is lifted, the arc will be transferred to the tube between the contact member 38 and the upper end of the arcing rod. When this occurs, the arc will melt a minute portion of the contact rod 45 and gasefy it, due to the intense heat. This will create an upward pressure in the tube which will assist the moving horns 16 in raising the interrupter tube to the top of its stroke and thus rupture the arc by very rapid attenuation. When the lower end of the contact rod 45 is burned off, it can easily be re-adjusted to make good contact with the upper end of the arcing rod 31.

The arc drawn in the tube is ruptured or extinguished before the tube reaches the upper limit of its stroke. The stroke is shown as being limited by means of an annular stop collar 48 adjustably mounted on the arcing rod 31, so that the hub-shaped guide member 33 strikes it as the tube is lifted by the movable arcing horns 16 and the free ends of the horns slide out of engagement with the cap during the final opening movement of the blade. The hot gas or flame is discharged downwardly from the tube into the trough-shaped member 29, and the flange 30 prevents it from damaging the stationary contact. Thus, the trough-shaped member serves the dual purpose of supporting the tube and acting as a shield for protecting the stationary contact of the switch.

When the arc is extinguished, the tube will fall by gravity to the re-set position, shown in Fig. 5. During the closing movement of the switch, the fork-shaped arcing horns 16 will straddle the upstanding, contact rod 45 and will be guided over the top of the cap by the cam-shaped ribs 42 to straddle the stationary U-shaped horn 26. Incidentally, the width of the U-shaped horn corresponds with the diameter of the tube 32, so that the forks of the arcing horns 16 will readily engage the shoulders 43 at the bottom of the cap when the switch is open and the forks are disengaged from the stationary horn.

From the foregoing description, it will be seen that the arc extinguishing attachment is very simple in its construction and operation. It is

so designed that it can be applied to airbreak switches of different types and has proved to be effective in breaking heavily loaded circuits without damage to the switch.

Obviously, the invention is not restricted to the particular embodiment thereof herein shown and described, but is capable of various modifications within the scope of the appended claims.

What is claimed is:

1. An arc extinguishing attachment for an air-break switch having a vertically swinging blade and a pair of parallel arcing horns, comprising a vertically movable interrupter tube of insulating material mounted on the stationary contact and having a metal cap member at its upper end; and a stationary arcing conductor rod electrically connected to the stationary switch contact and supported within the tube with its upper end normally in contact with said metal cap; the movable arcing horns being engageable with said cap as the switch blade is raised to its open position to lift the tube and start an arc between the cap and the arcing conductor rod, whereby gas pressure created by the arc will force the tube upwardly to elongate and extinguish the arc.

2. An arc extinguishing attachment for an air-break switch, as set forth in claim 1, wherein the arcing conductor rod and movable tube are mounted on a bracket secured to the stationary switch contact; and a hub-shaped guide member slidably mounted on the arcing conductor rod connected to the bottom of the tube to confine the tube to move vertically on the rod; and a stop member on the rod coacting with said guide member to limit the upward movement of the tube.

3. An arc extinguishing attachment for an air-break switch, as set forth in claim 1, wherein the arcing conductor rod and movable tube are supported on a bracket secured to the stationary switch contact; a vertical, inverted, U-shaped arcing horn parallel with and adjacent to said tube terminating slightly below the cap on said tube and positioned to be straddled by the arcing horns on the switch blade, whereby the current flow is established through the tube cap and arcing conductor rod as the movable arcing horns are swung above the U-shaped horn; means to guide the tube to slide upwardly on the conductor rod; and means to limit the upward movement of the tube.

4. An arc extinguishing attachment for an air-break switch, as set forth in claim 1, wherein the cap on said tube has a plurality of vertical ribs to act as spreading cams for the horns; and said ribs having shoulders at their bottom edges to be engaged by the movable arcing horns.

5. An arc extinguishing attachment for an air-break switch having a vertically swinging blade and a pair of parallel arcing horns, comprising a vertically movable interrupter tube of insulating material mounted on the stationary contact and having a metal cap member at its upper end; a stationary arcing conductor rod electrically connected to the stationary switch contact and supported within the tube with its upper end normally in contact with said metal cap; the movable arcing horns being engageable with said cap as the switch blade is raised to its open position to lift the tube and start an arc between the cap and the arcing conductor rod, whereby gas pressure created by the arc will force the tube upwardly to elongate and extinguish the arc; vertical cam-shaped ribs on the cap acting as spreading cams for the horns; said ribs having

shoulders at their bottom edges to be engaged by the movable arcing horns; a vertical, inverted, U-shaped horn spaced from the tube with its upper end terminating short of the cap on the tube; and a short conductor rod extending through and adjustably connected to the cap in contact with the upper end of said arcing conductor rod.

6. An arc extinguishing attachment for an air-break switch, as set forth in claim 1, wherein the arcing conductor rod and movable tube are supported on a horizontal trough-shaped member with the lower, open end of the tube above the bottom of said trough-shaped member, said

5 trough-shaped member being shaped and positioned to discharge the arc flame and hot gases rearwardly from the switch to prevent burning the adjacent contact of the switch.
